DESIGN FOR A VASE

Elsie Luthy Fitzgerald, San Antonio, Tex.

Application November 29, 1945, Serial No. 124,204

Term of patent 7 years

(Cl. D29—28)

To all whom it may concern:

Be it known that I, Elsie Luthy Fitzgerald, a citizen of the United States, residing at San Antonio, in the county of Bexar and State of Texas, have invented a new, original, and ornamental Design for a Vase, of which the following is a specification, reference being had to the accompanying drawing, forming a part thereof.

Fig. 1 is a side perspective view of a vase showing my new design,

Fig. 2 is a similar view showing the opposite side of the vase from that shown in Fig. 1, and

Fig. 3 is a top perspective view thereof.

I claim:

The ornamental design for a vase, as shown.

ELsie LUTHY FITZGERALD.
